DIRIGIBLE

Hugo Karl Deubel, Hartford, Conn.

Application December 11, 1930, Serial No. 501,627

1 Claim. (Cl. 244—6)

This invention relates to certain new and useful improvements in dirigibles, and to landing and mooring means therefor.

The primary object of the invention resides in the construction of a dirigible having a depending gondola constructed to carry water ballast and designed to permit alighting of the dirigible upon a water surface and including stabilizing means whereby the dirigible may be 10 horizontally supported upon a body of water.

A further object of the invention is to provide an airship of the dirigible type wherein the dirigible body or gas bag is constructed of light corrugated metal for increasing the strength of 15 the body or gas bag and to lessen the number of struts required for the bracing of the dirigible body or gas bag.

Another object of the invention is to provide a dirigible of the foregoing character wherein side 20 fins or wings are supported on a frame-work that is rotatably adjustable and also carries a propeller and operating motor therefor whereby the side fins or wings together with the propellers may be shifted relative to the body of the dirigible 25 to aid in ascending and descending movement of the dirigible.

A further object of the invention is to provide control valves for the water ballast carried by the gondola to aid in the rise and descent of the 30 dirigible.

Another object of the invention is to provide a landing and mooring arrangement for the dirigible in the form of water runways in communication with a hangar arrangement with 35 apparatus for moving the dirigible from one of the runways into the hangar.

With the above and other objects in view that will become apparent as the nature of the invention is better understood, the same consists in 40 the novel form, combination and arrangement of parts hereinafter more fully described, shown in the accompanying drawings and claimed.

In the drawings:—

Figure 1 is a side elevational view of an airship of the dirigible type constructed in accordance with the present invention, showing the side propellers and fins, the depending gondola containing the water ballast and the stabilizing arms 50 or floats at one end of the dirigible body;

Figure 2 is an end elevational view of the dirigible;

Figure 3 is a bottom plan view of the gondola showing the construction that permits the charging 55 of the gondola with water ballast;

Figure 4 is a fragmentary end elevational view of the gondola;

Figure 5 is an enlarged fragmentary side elevational view, partly broken away of the forward end of the gondola;

60

Figure 6 is an enlarged fragmentary side elevational view of the rear end of the gondola showing the anchor drag net associated therewith;

Figure 7 is a vertical cross-sectional view taken on line 7—7 of Figure 1 showing the corrugated 65 construction of the dirigible body or gas bag with the gondola depending therefrom and the water ballast therein;

Figure 8 is an enlarged fragmentary sectional view showing the valve and operating mechanism 70 associated with the ballast means in the gondola;

Figure 9 is a fragmentary side elevational view of the frame or bearing carrying a side wing or fin and propeller, the motor associated with the bearing and the worm wheel for rotating the 75 bearing;

Figure 10 is an elevational view of the arrangement shown in Figure 9 looking toward the outer end of the bearing;

Figure 11 is an end elevational view of the other 80 end of the bearing showing the motor;

Figure 12 is an enlarged fragmentary side elevational view of the forward end of the dirigible;

Figure 13 is a top plan view of the landing and 85 mooring arrangement for the dirigible and illustrates the water runways in communication with a hangar runway with the cover of the hangar removed and the devices for moving a dirigible into the hangar runway;

90

Figure 14 is a longitudinal sectional view taken on line 14—14 of Figure 13; and

Figure 15 is a cross-sectional view taken on line 15—15 of Figure 13.

Referring more in detail to the accompanying 95 drawings, there is illustrated an airship of the dirigible type comprising a body portion or gas bag 1 having the usual thin fabric or metal covering 1a and a tubular liner of corrugated metal 2 as shown in Figure 7 for increasing the 100 strength of the gas bag and thereby lessening the number of struts required for internal bracing structure, the central tube portion 3 of the body 1 having tie rods or cables 4 radiating therefrom and anchored at their outer ends to the ring 5. 105 The rear end of the body 1 of the dirigible is equipped with the usual rudder 6 and elevator 7 operated by mechanism not shown.

A gondola 8 depends from the forward part of the dirigible body 1 and as shown in Figures 110

- 4 to 8 includes a sub-structure 9 providing water ballast chambers 10, the bottom wall of the sub-structure or water ballast chamber being designated by the reference numeral 11. The bottom wall 11 of the water ballast chamber as illustrated in said figures and shown in bottom plan view in Figure 3 has spaced upwardly curved wall sections 12 extending transversely of the bottom with spaced openings in the bottom at 10 the upper edge of each pair of walls 12 that is covered by a screen or grill 13, the openings leading into the water ballast chamber 10 and being controlled by separate valves 14 operated by pneumatic devices 15 for opening and closing 15 the valves when it is desired to charge the chamber 10 with water for ballast purposes or to discharge the water ballast from said chamber, a valve and its operating device being illustrated in Figure 8.
- 20 As shown in Figures 1 and 6, the rear end of the gondola in line with the sub-structure 9 is equipped with a drag anchor 16 in the form of a water bucket or scoop and to which a cable 16a is attached for purposes presently to appear. To 25 maintain the dirigible in a level condition when floating or moving over a water surface, depending floats or stabilizers 17 are carried by the body portion 1 and any number thereof desired for accomplishing the results may be provided. 30 When the floats or stabilizers are out of use, they may be deflated so that least resistance possible is offered to the forward travel of the dirigible.
- The propelling devices for the dirigible are shown more clearly in Figs. 1, 7, and 9 to 11 and 35 include relatively large rotatably mounted bearings 18 set into the sides of the body portion 1 and each having a side fin or wing 19 projecting outwardly and supported by the framework 20 shown in Figure 9. The rotatable bearing 18 includes a framework having an outwardly directed 40 arm 21 and an inwardly directed support 22 for a motor 23. The shaft 24 of the motor extends outwardly of the bearing above the arm 21 and enters a gear box 25 for transmitting motion to 45 the propeller blade 26, it being understood that the dirigible may carry any number of propellers desired. As an aid to the elevator 7 to effect the rise and descent of the dirigible in travel, the 50 bearings 18 may be rotatably adjusted for raising or lowering the front edges of the fins 19 and to 55 change the direction of propelling force of the propellers 26 relative to the body portion 1 and to accomplish this result, the rotatable bearing 18 is provided upon one side thereof with worm teeth 56 27 as shown in Figure 9 as engaged by the worm 28 shown in Figure 10.
- An important feature of this invention is the 60 landing and mooring construction for the dirigible as shown in Figs. 13 to 15. A concrete or other foundation 29 is designed to provide water runways 30 radiating from a central channel 31 and 65 one of said runways constitutes a hangar 32 covered by a frame structure 33 so that the dirigible may float upon water when housed or moored. As shown in Fig. 14, the dirigible A is illustrated as alighting upon the surface of the water in one of the runways 30 and has dropped the drag anchor 16 to aid in alighting. The dirigible B is floating upon the surface of the water in one of the runways 30 as shown in Figs. 13 and 14 and is anchored by cables 34 to the side rail 35 of a runway. The cable 36 attached to the forward end of the dirigible is employed for moving the dirigible into the hangar runway 32, the side cables 34 being released, the draft cable 36 passing over a guide pulley 37 on a side of the runway 32 and engaged with the hook of the crane 38 that is movable over the track 39 and operated by the motor 40, the cable 36 moving the dirigible from one of the runways 30 into the hangar runway 32 to assume the position as at C.
- From the above detailed description of the invention, it is believed that the construction and operation thereof will at once be apparent, it being understood that the water ballast chamber 10 may be charged with water from the runways 30 and the discharge of the water ballast is under control of the valve 14 operated by the pneumatic devices 15, the water outletting through the screened openings 13. It is also to 105 be noted that the dirigible may travel upon the surface of water by being maintained in a level condition provided by the sub-structure 9 of the gondola and the stabilizing floats 17. Rise and descent of the dirigible may be increased by rotating the bearings 18 which carry the side fins 19 and propellers 26 while the mooring arrangement provides a hangar inclosure for the dirigible as well as a water supply for the ballast. As 110 stated, the drag anchor is in the form of a bucket 115 or scoop and as the carrying cable 16a for the same may be of considerable length, the bucket or scoop 16 may be lowered into a body of water as shown in Fig. 14 for purposes of recharging the water ballast chamber 10 without the 120 necessity of landing the dirigible on a body of water.
- I claim:—
- In a dirigible, a body portion, a gondola depending therefrom and having a sub-structure 125 including a water ballast chamber, the ballast chamber being divided into separate compartments, a screened outlet opening for each compartment, a separate valve for each outlet opening and a cable supported drag bucket carried 130 by the dirigible at the rear end of the sub-structure with the open side of the bucket facing the sub-structure for charging the ballast chambers with water during flight of the dirigible.

HUGO KARL DEUBEL.
